[57] CLAIM

The ornamental design for an air guide for motor vehicle rear windows, as shown and described.

DESCRIPTION

FIG. 1 is a rear elevational view of the air guide for motor vehicle rear windows showing our new design; FIG. 2 is a left side elevational view of FIG. 1, the right side being substantially a mirror image thereof; and FIG. 3 is a left rear perspective view of FIG. 1. The broken lines in the drawing are for illustrative purposes only.
